UNITED STATES PATENT OFFICE.

WILLIAM H. H. WOOD, OF BROOKLINE, MASSACHUSETTS.

CHECK-BOX FOR RESTAURANTS.

SPECIFICATION forming part of Letters Patent No. 225,036, dated March 2, 1880.

Application filed May 14, 1879.

To all whom it may concern:

Be it known that I, WILLIAM H. H. WOOD, of Brookline, in the county of Norfolk and State of Massachusetts, have invented certain new and useful Improvements in Check-Boxes for Restaurants, &c.; and I do hereby declare that the following specification, taken in connection with the drawings furnished and forming a part thereof, is a true, clear, and exact description of my invention.

My improved check-boxes involve various novel features in construction and arrangement with relation to each other of the several parts, many of which parts have been heretofore employed in various ways in fare and in check boxes, and the object sought by me is a check-box which will afford opportunity for supervision from a distance, so that one or more boxes in any one room more or less remote from the inspector and from each other may be readily scrutinized, and at the same time be well guarded against any surreptitious attempts at withdrawing checks therefrom.

My invention consists in a check-box embodying a glass front, an induction-aperture above the glass, a guard-plate in said aperture, a movable check-controller, parallel with the rear of the glass front, closely adjacent thereto, for flatly holding the deposited checks against the glass, a knob for externally operating the controller, and a receptacle below the controller, into which the checks are finally deposited after a movement parallel with the glass in their passage from the induction-aperture.

To more particularly describe my said improvements, I will refer to the accompanying drawings, in which—

Figure 1 represents, in front perspective, a check-box embodying the several features of my invention. Fig. 2 represents the same in central vertical section. Figs. 3 and 4 represent, respectively, in front view and in central vertical section on line $x y$, a check-box embodying the main feature of my invention.

The box A, Figs. 1 and 2, may be made in any desired form, of cast metal or wood, provided with a door at the rear, affording access to all parts of the interior, for the removal of checks or the adjustment of the mechanism;

and said door should be provided with a suitable lock for securing the contents against all unauthorized persons. The front of the box is mainly of heavy glass, as at a . The check-controller B, in Figs. 1 and 2, is of the character preferred by me, and is composed of an endless belt, b , mounted on rolls, the axis of one of which extends through the ends of the box, and is provided with a hand wheel or 60 wheels, c , whereby the check-controller may be rotated with a considerable proportion of its surface parallel with the rear of the glass front and in close proximity thereto.

At the top of the box, adjacent to its front, 65 is an induction-aperture, C, capable of receiving a pasteboard or other check edgewise and guiding its lower edge to a point between the coincident surfaces of the check-controller and the glass, so that when the hand-wheel c is 70 turned in the proper direction the check will be carried downward and held flatly against the glass, and thereby enable a purchaser or any other person to be assured that a check representing the amount of cash paid has 75 been duly deposited, to be subsequently accounted for.

For assuring a more complete control over the checks the endless belt is provided with slightly-projecting lateral cross-pieces b' , of 80 flexible material, located at regular intervals.

For rendering the induction-aperture C practically secure against the withdrawal of a check once inserted, it is provided with a stop-plate having a sharp delicate lower edge, d , 85 which, by its defacement incident to the use of any sharp retractile instrument, would be so far defaced as to disclose the surreptitious attempt. Beneath the endless belt is a receptacle, which, in this instance, consists of the 90 lower portion of the box or chamber, within which the checks are deposited after such display as has been afforded by the check-controller.

The box shown in Figs. 3 and 4 has a check-controller, B', which is capable of maintaining a check in an exposed condition, and is movable for the release of the check into the receptacle below. Instead of being a revolving endless belt it is flat-surfaced, rigid, parallel with the rear side of the glass front a' , and is maintained in proper check-holding re-

lation with the rear of the glass front by means of suitable springs. Instead of hand-wheels, as in the other form of box, this check-controller is provided with a draft-rod, D, which 5 projects outward through the rear wall of the box, and is provided with a handle, whereby the check-controller may be moved rearward at will for releasing a check. The guard-plate d, previously described, is applied in like manner to this form of box.

In order that a separation may be readily afforded between the checks deposited by one person and the next succeeding person on duty, I provide at the rear of the box, either 15 in the door thereof or below it, a long narrow aperture, e, through which a thin parting-card may be inserted, to serve as a means of separating the several checks deposited by one person from those deposited by his successor.

20 It is to be understood that the object of this box is to perfect the accounting system heretofore imperfectly provided for in various ways, and it is an important feature in my check-box that the checks while held by the check-controller against the glass are visible, for instance, across a store, so that persons whose interest it is may take either a general or special cognizance of a cash transaction just completed; and as this involves necessarily 25 the use of checks with large plainly-inscribed figures, I have devised a system of checks particularly adapted for use in restaurants and other places, in which the color of the check is in itself a partial indication of the general 30 value to be represented, the figures thereon relating to the details—as, for instance, in a bar-room a red check would denote ten-cent 35 drinks, and the number thereon the particular number of drinks sold of that value, and so on throughout the range of prices; but said 40 system of checks constitutes no portion of my present invention, as I propose to make it the subject of a separate application for Letters Patent.

45 I am well aware that glass fronts for fare-

boxes are not new; but I know of none in which a movable check or fare controller at the rear of the glass is employed, wherein the checks are flatly held against the glass during their passage to the receptacle below. 50

I am also well aware that endless belts have been heretofore employed, arranged to be operated solely by the weight or gravity of metal checks or coin, and also that endless belts have been employed in the flexible arms of portable 55 fare-boxes for conveying fares or tickets from the end of the flexible arm to the box, and in this latter class of devices external means are employed for operating the belt; but I know of no prior endless belt or equivalent device so 60 arranged with relation to a glass front that a check could be flatly held against the glass during its entire passage to the receptacle, and externally operated, so that paper checks could be used therewith as well as heavy 65 checks or coin. The guard-plate employed by me is an important element, because therewith a check once within the custody of the controller cannot be withdrawn, but must be permitted to pass to the accounting-receptacle. 70

Having thus described my invention, I claim as new and desire to secure by Letters Patent—

The check-box embodying, in combination, the glass front, the induction-aperture above 75 the glass, a guard-plate in said aperture, the movable check-controller, parallel with the rear of the glass front and closely adjacent thereto, for flatly holding the deposited checks 80 against the glass, a knob for externally operating the controller, and a receptacle below the controller, into which the checks fall when released by the controller after having moved parallel with the glass in their passage from the induction-aperture, substantially as de- 85 scribed.
